UNITED STATES PATENT OFFICE.

CHARLES J. LYONS, OF MINNEAPOLIS, MINNESOTA, ASSIGNOR TO AMANDA C. LYONS,
OF MINNEAPOLIS, MINNESOTA.

CONCRETE-BLOCK MACHINE.

Application filed September 18, 1923. Serial No. 663,403.

To all whom it may concern:

Be it known that I, CHARLES J. LYONS, a citizen of the United States, residing at Minneapolis, in the county of Hennepin and 5 State of Minnesota, have invented certain new and useful Improvements in Concrete-Block Machines; and I do hereby declare the following to be a full, clear, and exact 10 description of the invention, such as will enable others skilled in the art to which it appertains to make and use the same.

This invention relates to a machine for making concrete blocks or similar molded articles. Concrete blocks are now 15 commonly used in various building operations and are usually made in a mold box in which the material is placed and tamped by reciprocating plungers.

It is an object of this invention to provide 20 such a machine comprising a plurality of preferably reciprocating tamping plungers operated by differentially arranged double lifting cams.

It is a further object of the invention to 25 provide such a machine having a locking means for each plunger to hold the same in elevated position, which locking means have a common operating member, the operation of which is controlled by the driving shaft 30 which operates said plungers.

It is still another object of the invention to provide such a machine as above stated in which the locking means and mechanism for operating the same may be adjusted to 35 lock the plungers after any desired number of reciprocations.

These and other objects and advantages of the invention will be fully set forth in the 40 following description made in connection with the accompanying drawings in which like reference characters refer to the same parts throughout the different views, and in which—

Fig. 1 is a view in front elevation of the 45 machine;

Fig. 2 is a vertical section taken substantially on the line 2—2 of Fig. 1, as indicated by the arrows;

Fig. 3 is a partial plan view of the 50 machine;

Fig. 4 is a vertical section taken on the line 4—4 of Fig. 1;

Fig. 5 is a horizontal section taken on the line 5—5 of Fig. 1;

Fig. 6 is a partial plan view of the machine;

Fig. 7 is a fragmentary vertical section showing the structure of the cam used; and

Fig. 8 is a horizontal section taken on the line 8—8 of Fig. 7, Figs. 3 to 8 being shown 60 on an enlarged scale.

Referring to the drawings, the machine comprises a frame having four upright posts 1 rectangularly arranged and which are connected by the transverse members 2 and the forwardly and rearwardly extending members 3. The lower members 2 and 3 carry a platform 4 on which is supported the mold box 5 which receives the concrete and in which the block is tamped and 70 formed. The frame members 1 are further connected by forwardly and rearwardly extending members 6 below the lowermost members 2 and 3.

Secured to the spaced forward members 75 2 are guide bars 7 from which project spaced pairs of lugs 8, the space between the lugs of the respective pairs being formed with right-angle corners. Guided between the lugs of the respective pairs are vertically reciprocating plunger members 9, each of which is formed of reversely arranged angle bars 10 spaced by and secured to rearwardly projecting lifting dogs 11. The forwardly disposed sides of the angle bars 80 10 move in contact with the bars 7 while the edges of said sides move in contact with the inner sides of the lugs 8. The lugs 8 are bored to receive headed and nutted bolts 90 on which are journaled the rollers 12, which rollers are arranged to contact with the rear surfaces of the forwardly directed sides of the angle bars 10. The plungers 9 are thus held firmly in vertical position for reciprocation.

Secured to the lower ends of the 95 plungers 9 are tamping heads 13. Each tamping head is formed of two similar parts 14 having flat bottom surfaces, said parts having their forward and rearward sides of rectangular shape, the sides adjacent each other being of smaller dimension than the remote sides and merging into said remote sides on a curve. The upper portions of the parts 14 are formed as flat

rectangular shanks 14^a which are received and carried between clamping yokes 15 at each side thereof and connected thereto by the headed and nutted clamping bolts 16 5 extending through said shanks and yokes. The yokes 15 are also recessed to receive the lower ends 9^a of the plungers 9, which ends are also connected to the yokes 15 by the headed and nutted bolts 17. It will be 10 noted, as shown in Fig. 1, that the portions 10^a are continuations of the rearwardly directed sides of the angle bars 10.

The plungers 9 are alternately lifted and dropped by cams 18 mounted upon a driving 15 shaft 19 extending transversely across the machine and journaled in bearings 20 secured to the intermediate members 3, which shaft is equipped with a driving pulley 21 at one side of the machine. There is a cam 20 18 for each plunger 9 and each of said cams comprises a hub member 22, as shown in Figs. 7 and 8, secured to the shaft 19 by a suitable set screw, which hub has a circular central flange thereon. Bifurcated arms 23 25 are bolted to said flanges at their inner portion and at their outer portion have journaled therein rollers 24 carried on suitable headed and nutted bolts extending through the outer bifurcated portions of said arms. 30 There are two arms 23 for each of the hubs 22 and said arms are disposed substantially at an angle of ninety degrees. As shown in Fig. 2, the cams are so arranged as to co-operate with the under surface of the lifting 35 dogs 11.

Locking means are provided for holding the plungers 9 in elevated position which comprises bell crank levers 25 mounted in angle brackets 26 secured to the forward 40 intermediate member 2. The levers 25 have an upstanding arm provided with a forwardly extending projection 26 adapted to extend rearwardly between the angle bars 10 and to engage the undersurface of the lower lifting dog 11. The levers are normally urged to such position by tensile 45 spring 27 secured adjacent the outer ends of the forwardly projecting arms of said levers and to the upper forward member 2. The levers 25 are held in inoperative position indicated in dotted lines in Fig. 4, or 50 permitted to assume operative position by a transverse bar 28 guided in a slotted bracket 29 mounted on the forward intermediate member 2 and secured at its other end to an intermediate point in a downwardly 55 projecting handle lever 30 which is pivoted at its upper end to the upper forward member 2. The bar 28 is provided with a plurality of slots 28^a, one for each of the levers 25, in which the forwardly projecting arm of said lever may rise to allow the lever to move to operative position. At one side 60 of each slot the bar is provided with a down-

wardly inclined cam surface adapted to engage and depress the forwardly projecting arms of lever 25 when the bar is moved longitudinally. The bar 28 is connected at its end opposite to lever 30 to a horizontally swinging lever 31 which passes through said bar and extends to the rear of the machine where it is secured by a vertical pivot to the rear intermediate member 2. The intermediate portion of the lever 31 is recessed to fit over the driving shaft 19 which is 70 equipped with screw threads 19^a so that the said portion of lever 31 acts as a nut on said thread. The forward end of the lever 31 is bent downwardly and pointed and serves as an indicating pointer co-operating with 75 graduations 32 formed on the front side of the forward intermediate member 2.

In operation, the mold box 5 to be tamped will be filled with the concrete material and placed in position under the tamping heads 80 13. The driving shaft 19 will now be driven by a suitable belt applied to the pulley 21. The cams 8 will be driven and the rollers 24 thereof will engage the lifting 85 dogs 11. The advancing roller 24 will engage the upper dog 11 and lift the plunger a certain distance when the following roller will engage the lower dog 11 and further lift the plunger. The following roller then moves from under the lower dog 11 and the 90 plunger is allowed to drop, the tamping head 13 striking the material in the mold and pressing the same. The cams 18 are equally spaced about the shaft 19 so that the plungers 9 are lifted at different times. 95

If it is desired to hold the levers in elevated position, the bar 28 can be moved to allow the forwardly projecting arms of levers 25 to move into the slots 28^a and the projections 26 will then move under the lifting 100 dogs 11 when the plungers are sufficiently raised. The plungers will thus be held in elevated position by the levers 25. The machine can be arranged so that the plungers will make several reciprocations and then be held in elevated position. This is done by disposing the lever 31 in the screw thread 105 19^a. As the shaft 19 revolves the lever will be moved by the screw threads and will move bar 28. When the bar has been moved to allow the levers 25 to move said levers will come into position to hold the plungers elevated. It is obvious that by placing the lever in any desired position on the screw 110 19^a that the plungers will be tripped after 115 making the desired number of reciprocations. The reciprocation of the plungers can then again be resumed by operating the lever 30, at which time the lever 31 moves over the threads 19^a.

From the above description it is seen that applicant has provided a very simple and efficient machine for tamping and making

the concrete blocks. The parts of the machine are few and easily and ruggedly made and the machine will operate with a minimum of attention for maintenance and repair. The machine has been amply demonstrated in actual practice and found to be very successful for the purpose intended.

It will, of course, be understood that various changes may be made in the details, arrangement and proportions of the parts without departing from the scope of applicant's invention, which, generally stated, consists in a device capable of carrying out the objects above stated and such as shown and described and set forth in the appended claims.

What is claimed is:

1. A concrete block machine having in combination, a frame, a plurality of plungers vertically reciprocable therein, a driving shaft, a lifting cam on said shaft for each plunger, a locking device for each plunger for holding the same in elevated position, and a common means operated by said driving shaft for positioning all of said locking devices in operative position.

2. A concrete block machine having in combination, a frame, a plurality of plungers vertically reciprocable therein, a driving shaft, a cam for each plunger having two circumferentially spaced lifting rollers, two lifting dogs on each plunger co-operating, respectively, with said rollers, said cams being equally spaced about said shaft.

3. A concrete block machine having in combination, a frame, a plurality of plungers vertically reciprocable therein, a driving shaft, a lifting cam on said shaft for each plunger, a locking device for each plunger, comprising a bell crank lever normally tending to move to operative position, a bar contacting one arm of all of said levers, said bar having spaced notches therein and inclined cam surfaces adjacent said notches and being movable to permit said arms of the bell crank levers to move, respectively, into said notches or to cam said arms downwardly to move the levers to inoperative position.

4. The structure set forth in claim 3, a screw on said driving shaft, a swinging arm connected to said bar and engaging said

screw to be moved thereby and move said bar.

5. A concrete block machine having in combination, a frame, a plurality of plungers vertically reciprocable therein, a driving shaft, a lifting cam on said shaft for each plunger, means on said driving shaft for differentially lifting said plungers, a locking device for each plunger to hold the same in elevated position, a common means for controlling all of said locking devices, means on said driving shaft for operating said last mentioned means including an adjustable member engaging the means on said driving shaft whereby the plungers can be locked after making different numbers of reciprocations.

6. A concrete block machine having in combination, a frame, a plurality of plungers vertically reciprocable therein, spaced guiding means for said plungers, each comprising a bar having pairs of spaced projecting lugs, said plungers contacting said bar at one of their sides and contacting said lugs with their edges, and rollers carried by said lugs contacting the other side of said plungers.

7. A concrete block machine having in combination, a frame, a plurality of plungers vertically reciprocable therein, said plungers each comprising spaced parallel angle bars, lifting dogs between said bars to which they are secured, and tamping heads secured to the lower ends of said bars.

8. A concrete block machine having in combination, a frame, a plurality of plungers reciprocable therein, a driving shaft, a lifting means on said shaft for each plunger, a spring actuated stop for each plunger, means engaging said stops for holding the same in inoperative position and movable to permit the same to move to operative position, and means directly engaging said drive shaft and operated thereby for moving said member.

9. The structure set forth in claim 1, said means comprising a bar movable transversely of said plungers and a member engaging a screw on said driving shaft for moving said bar.

In testimony whereof I affix my signature.
CHARLES J. LYONS.
